UNITED STATES PATENT OFFICE.

IDA R. BURDICK, OF GLOVERSVILLE, NEW YORK.

ORNAMENTAL-STITCH MACHINE.

SPECIFICATION forming part of Letters Patent No. 662,185, dated November 20, 1900.

Application filed February 26, 1900. Serial No. 6,620. (No model.)

To all whom it may concern:

Be it known that I, IDA R. BURDICK, a citizen of the United States, residing at Gloversville, in the county of Fulton and State of New York, have invented a certain new and useful Improvement in Tambouring-Machines, of which the following is a full, clear, and exact description.

The main object of this invention is to provide a simple and economical machine for stitching the backs of gloves, although the machine is applicable for stitching or tambouring generally.

In carrying out my invention I use a vertically-reciprocating hook and a vibrating feed mechanism for feeding the material longitudinally and laterally—that is to say, in two directions, one substantially at right angles to the other—so as to make a zigzag line of stitches. The thread is fed from below the material-feed mechanism and is engaged by the hook through the intervention of a looper and is looped through the material and laid upon the upper and right side of the material in plain sight of the operator, all as I will proceed now more particularly to set forth and finally claim.

In the accompanying drawings, illustrating my invention, in the several figures of which like parts are similarly designated, Figure 1 is a side elevation, the cloth-plate being in longitudinal section of a well-known form of sewing-machine having my improvements applied. Fig. 2 is a horizontal section just below the cloth-plate. Fig. 3 is a left-hand end elevation. Fig. 4 is a perspective view of the vibrating cam details. Fig. 5 is a perspective view of the looper and its holder. Fig. 6 is a plan view of the presser-foot. Fig. 7 is a perspective view of the hook and cast-off. Fig. 8 is a diagram illustrating one form of stitch.

I have selected a well-known form of sewing-machine to illustrate my invention, but wish to be understood as contemplating the application or adaptability of my invention to other forms of machines.

The pedestal or bed *a*, its wall *a'*, the overhanging arm *b*, having guide-bearings *b'* for the vertically-reciprocating bar *c*, the bar-reciprocating lever *d*, fulcrumed at *d'* to the overhanging arm and connected by an eccen-

tric link *e* with the rotary main shaft *f*, the presser-foot *g* and its spring-depressed bar *g'* and lifter *g''* may be of any approved construction, excepting that the presser-foot has a large triangular opening, as shown in Fig. 6, and is capable of vibrating with the feed-dog *h* and its carrier *h'*, as will appear more fully presently. The cloth-plate *i*, secured to the upper surface of the wall *a'*, may also be as usual. The openings in the feed-dog and the cloth-plate are also enlarged to provide for the lateral movement of the material. The main shaft has a switch-cam *j*, which is engaged by a shoe *k*, swiveled in a head *k'* on a rod *k''*, which is adapted to slide lengthwise in a post *k'''* and the wall *a'*. A lever *l* is pivoted at one end to a post *l'*, projecting from the wall *a'* or otherwise supported, and its other end *l''* is applied to the rod *k''*, and between these ends is pivoted to said lever a link *l''*, which is supported to slide back and forth in the wall *a'*. At its free end this link *l''* engages the proximate slotted end of the feed-dog carrier *h'*. The feed-dog carrier has a rear forked end to engage a pivot-pin *m*, and between its ends said carrier is provided with a slot in which rotates the cam *n* on the main shaft to give to said carrier and feed-dog the usual back-and-forth and up-and-down feed motions, and during these motions the lever *l* through the link *l''* imparts a lateral vibration to the said feed-dog and carrier. The under side of the cloth-plate is provided with a thread-guide *o*.

The looper is composed of a thread-carrier *p*, here shown as of coiled wire of V shape, having the coil *p'* for carrying the thread in the apex of the V. This thread-carrier is secured in any suitable manner, as by one of its arms *p''*, to an upright bar or holder *q*, which is pivoted to swing toward and from the wall *a'* in a rocker-stud *q'*, mounted in the wall *a'*. This holder *q* is normally drawn rearwardly by a coiled or other spring *r* and is also normally drawn toward the wall *a'* by a coiled or other spring *r'*, so as respectively to cause a pin *s* on the holder and the rear face of said holder to engage, respectively, the periphery of a cam *t* and a face-lump *t'* of said cam, which cam is mounted upon the end of the shaft *f*.

I employ a hook *u* instead of a needle in

the bar *c* and provide therefor a coöperating cast-off *v*. This cast-off is secured to a slide-bar *v'*, mounted upon the bearings *b'* by screws *v*² passed through slots in said slide-bar into 5 said bearings, and said slide-bar is held in given position by a friction-spring *v*³, borne by the overhanging arm. The slide-bar is provided with a lengthwise slot *v*⁴, which is engaged by a pin *v*⁵ on the bar *c*.

10 The take-up *w* is a wire supported in the wall *a'* and having one end *w'* extending into the path of movement of a pin *w*² on the switch-cam and having its other end slightly bent and crossing the path of the thread, so 15 that said take-up is positively vibrated at intervals to actuate the end *w*³ properly to apply pressure upon the thread.

I have thus described the illustrated form and application of my invention to one type 20 of well-known sewing-machine, but, as previously noted, mean not to limit my invention thereto. I will proceed now to describe the operation.

Thread having been supplied from a spool 25 or other source is passed through the guide *o* over the end *w*³ of the take-up, thence through the looper-eye *p'* and up through the cloth-plate. Motion being given to the main shaft, the hook descends and catches the 30 thread, which is then bent about it in the form of a loop by the back-and-forth motions imparted to the looper by means of the periphery of the cam *t* engaging pin *s* and the retractile force of spring *r*, and the lateral vibrations of said looper are effected by the face-lump *t* engaging the back of the looper-holder to force it away from the hook and the retractile spring *r'* to draw it toward the hook. The feed-dog is given its usual back-and- 40 forth and up-and-down motions and in addition has a vibratory motion toward and from the wall *a'* imparted to it by the link *l*², which motion, being compounded with the back-and-forth and up-and-down motions of the 45 feed-dog, results in giving a zigzag line of stitches, and these stitches are laid upon the upper and right side of the material in plain view of the operator. Such a line of stitches or loops is shown in full lines in Fig. 8, and, 50 if desired, the first-laid line may be over-stitched by a second line, the stitches of which cross the first-laid stitches at about right angles, as indicated by the dotted lines in Fig. 8.

It will be observed that the cast-off is carried up with the hook-bar and is there held by the friction-spring while the hook is descending for the next loop and until the pin *v*⁵ on the bar reaches the end of its slot in the bar *v'*, and then it is carried down, and there 60 is a like dwell of the cast-off in the ascent of the hook. Since the cast-off hugs the hook and on its barb side there is a coöperation between them which insures the proper formation and interchaining of the successive 65 loops.

It will be noticed that the area of toothed feed-dog surface is quite large and a large

presser-foot is employed and contact is intimate between them, and all this is necessary in order properly to do glove or leather work. 70 The hole, however, in the throat-plate for the hook is not enlarged, but is of a size complementary to the hook.

What I claim is—

1. The combination of a feed-dog, means to 75 impart to it back-and-forth and up-and-down motions, and means to vibrate it laterally, with a stitch-forming mechanism including a reciprocating hook and a cast-off therefor, a complementary looper constructed as a thread-carrier, a pivoted holder for such looper, means to reciprocate said looper and its holder longitudinally and laterally with relation to the feed-dog, a take-up and means to vibrate it, substantially as described. 85

2. The combination of a feed-dog, means to 90 impart to it back-and-forth and up-and-down motions, and means to vibrate it laterally, with a stitch-forming mechanism including a reciprocating hook, a complementary looper 95 constructed as a thread-carrier and receiving the thread from below, a pivoted holder for such looper, means to reciprocate said looper and its holder longitudinally and laterally with relation to the feed-dog, a take-up and means to vibrate it, substantially as described.

3. A machine for stitching the backs of 100 gloves, and for stitching other objects, with zigzag lines of stitches laid on the face or side exposed to the operator, comprising a reciprocating hook, to which a single thread is supplied from below, and a looper-holder pivotally connected to a fixed portion and adapted to be vibrated across the path of the descending hook and transversely thereto, a cam having peripheral and face contact with said looper-holder, means to hold the looper-holder in operative contact with said cam, and means to impart a zigzag longitudinal feed to the material, substantially as described. 105

4. A machine for stitching the backs of 110 gloves, and for stitching other objects, with zigzag lines of stitches laid on the face or side exposed to the operator, comprising a reciprocating hook to which a single thread is supplied from below, a cast-off, a complementary looper constructed as a thread-carrier, a looper-holder pivoted at its lower end to a fixed portion, means to impart a back-and-forth and a laterally-vibrating movement to 115 said looper and its holder, and a material-feeding mechanism including a feed-dog having lengthwise, rising-and-falling and laterally-vibrating movements, substantially as 120 described. 125

5. A machine for stitching the backs of 130 gloves, and for stitching other objects, with zigzag lines of stitches laid on the face or side exposed to the operator, comprising a reciprocating hook, to which a single thread is supplied from below, a cast-off, a cast-off slide having a slot-and-screw attachment to the machine-head and a slot-and-pin connection

with the hook carrier or bar and thereby adapted to be intermittently reciprocated by the said hook carrier or bar, a complementary looper, and a material-feeding mechanism including a feed-dog having lengthwise, rising-and-falling and laterally-vibrating movements, substantially as described.

5 6. A machine for stitching the backs of gloves, and for stitching other objects, with 10 zigzag lines of stitches laid on the face or side exposed to the operator, comprising a reciprocating hook, to which a single thread is supplied from below, a complementary looper constructed as a thread-carrier, a looper-holder

pivotaly supported at its lower end and means 15 for giving it movement in directions transverse to one another, and material-feeding mechanism including a feed-dog having lengthwise, rising-and-falling and laterally-vibrating movements, substantially as de- 20 scribed.

In testimony whereof I have hereunto set my hand this 26th day of February, A. D. 1900.

IDA R. BURDICK.
